(57) **CLAIM**

The ornamental design for eyelash curler handle, as shown and described.

DESCRIPTION

FIG. 1 is a perspective view showing the front and left side of a eyelash curler handle of our new design;

FIG. 2 is a right side view thereof;

FIG. 3 is a front view thereof; and,

FIG. 4 is a rear view thereof.

In the drawings, the broken lines illustrate portions of the article which form no part of the claimed design.
